SYSTEM FOR HANDLING ABRASIVE
POWDER

Vanderveer Voorhees, Homewood, Ill., assignor to
Standard Oil Company, Chicago, Ill., a corpora-
tion of Indiana

Application October 31, 1940, Serial No. 363,640

9 Claims. (Cl. 196—52)

This invention relates to a system for handling abrasive powder and it pertains more particularly to the handling of powdered catalyst in hydrocarbon conversion processes for the manufacture of high quality motor fuel.

Powdered catalyst systems have been found to be far superior to fixed bed systems in many respects but a serious problem in powdered catalyst systems is that of handling the abrasive powder and particularly introducing this powder from a zone of low pressure to a zone of high pressure. Ordinary pumps or blowers cannot be used for this purpose because when powdered catalyst comes into contact with metal surfaces which are subject to sliding friction, the metal surfaces quickly become eroded and worn away by the abrasive action of the catalyst. A pressure screw of gradually diminished pitch has been proposed as a solution to this problem but the friction losses in such a screw are enormous and here again the erosion due to contact of catalyst particles with moving metal surfaces makes it necessary to replace metal parts at very short intervals. Pumps of the pressure screw type are also subject to the disadvantage that they are mechanically very inefficient and they cause an agglomeration of the catalyst which seriously impairs its activity. An object of my invention is to provide a means for handling powdered catalyst which will avoid the above difficulties.

Some appreciation of this problem may be apparent when it is considered that in a 20,000 barrel per day catalytic cracking plant it may be necessary to handle about 20,000 tons per day of powdered catalyst. This presents a chemical engineering problem of considerable magnitude. Screw pumps have been found to have mechanical efficiency of only about 1%. No other pump has been found which will stand up under the severe operating conditions required for handling this abrasive catalyst powder. Sliding friction between fast moving surfaces which may come in contact with the abrasive powder is, of course, utterly out of the question. An object of my invention is to provide a solution for this problem, to provide a commercially feasible pump for handling powdered catalyst and transferring it from a low pressure zone to a high pressure zone.

While my invention pertains primarily to the handling of powdered catalyst, it should be understood that certain aspects of my invention are likewise applicable to the handling of other abrasive powders. The invention will be described,

however, in connection with its application to a catalytic cracking system.

In practicing my invention I aerate the powdered catalyst to such an extent that it may be handled as a fluid. I then compress this fluid and transfer the compressed aerated powder from a low pressure zone to a high pressure zone while preventing the powder from contacting any metal surfaces which are exposed to sliding friction. These compressing and transferring operations are effected in a reciprocating surge pump which is provided with a molten metal seal. In one embodiment of the invention there is a surging back and forth of the molten metal itself in a pump chamber, the molten metal acting as a piston for drawing aerated catalyst into the pump chamber, compressing the aerated mixture and then discharging the aerated mixture to the zone of high pressure. In another embodiment of the invention the molten metal is merely employed as the seal around a reciprocating solid metal piston, but in this case that portion of the piston which actually comes in contact with powdered catalyst is not subjected to sliding friction.

The invention will be more clearly understood by reference to the accompanying drawing which forms a part of this specification and in which:

Figure 1 is a diagrammatic flow sheet of a catalytic cracking system employing one embodiment of my catalyst handling means.

Figure 2 is a modification of the catalyst handling means wherein the solid metal piston does not come into contact with the powdered catalyst.

While the invention is applicable to any hydrocarbon conversion process such as dehydrogenation, hydrogenation, aromatization, isomerization, alkylation, gas reversion, reforming, iso-forming, etc., it will be herein described as applied to the catalytic cracking of heavy hydrocarbons such as gas oils for the production of high octane number motor fuel.

A gas oil charging stock is introduced through line 10 and passed through coils 11 of pipe still 12 to transfer line 13 in which the vaporized gas oil may be at a pressure of about atmospheric to 50 pounds or more per square inch, preferably about 10 pounds per square inch, and at a temperature of about 875 to 1100° F., preferably about 925 to 950° F. Powdered catalyst from chamber 14 is introduced into transfer line 13, the catalyst-to-oil weight ratio being about 1:1 to 5:1, preferably about 3:1.

The catalyst is preferably of the silica-alumina

type such as acid treated bentonite, an alumina-silica gel composition or a natural or synthetic zeolite in which the alkali ions have been leached by acid or replaced by aluminum. Other forms of siliceous and aluminiferous materials, natural or artificial, may be employed. No novelty is claimed in a catalyst per se since such catalysts are well known to the art and a further description of such catalyst is unnecessary.

The average particle size of the catalyst is preferably from about 10 to 80 microns. When compacted such catalysts may have an apparent density of about .6 to .7—a cubic foot may weigh about 40 to 45 pounds. However, when this catalyst is slightly aerated it behaves as a fluid, the density of which depends upon the catalyst particle size and the linear velocity of the aerating fluid. At linear aerating fluid velocities of the order of about 1 foot per second or less the catalyst may have a density of about 25 pounds per cubic foot. With linear aerating vapor velocities of about 1 to 2 feet per second the catalyst may have a density of about 10 to 15 pounds per cubic foot. By varying the linear velocity of the aerating vapors the density of the fluid catalyst mass may thus be controlled and this fluid mass of powdered abrasive powdered catalyst material can be handled as a heavy gas or liquid.

The hot hydrocarbon vapors carry the catalyst introduced from chamber 14 into reactor 15 wherein catalytic conversion occurs. This reactor is designed to give the desired time of contact with vapors and catalyst holding time. For catalytic cracking the contact time may be about 5 to 25 seconds, preferably about 10 seconds, and the catalyst holding time may range from a minute to 15 minutes or more. The vapor velocity in the reactor may be about 1 to 3 or more feet per second.

When in balanced operation, reaction products carry the powdered catalyst out of the reactor at the same rate as powdered catalyst is introduced into the reactor. The withdrawn reaction product-catalyst mixture is passed by line 16 into cyclone separator 17 from which reaction products are passed by line 18 to a suitable fractionation system. It will be understood, of course, that a plurality of cyclone separators may be employed in series for obtaining more complete catalyst separation and that Cottrell precipitators or other suitable means may be employed for removing the last traces of catalysts from the hydrocarbon stream.

Catalyst from separator 17 is passed through star feeder 19 to receiver 20 of which the upper part functions as a stripping section and the lower part as a catalyst accumulator. Inert aerating and stripping gases may be introduced through line 21 and withdrawn through line 22, preferably leading to line 18 (by connection not shown). Additional stripping gas may be introduced at the upper part of chamber 20 so that aeration in the base of this chamber may be controlled to give the desired catalyst density which may be about 10 to 25 pounds per cubic foot.

It is now necessary to transfer this powdered catalyst from accumulator tank 20 which is at relatively low pressure to a regenerator system which may be at about 10 to 50 pounds higher pressure. To further complicate the problem, the catalyst at this stage is at a temperature of about 800 to 900° F. Ordinary pumps are utterly useless for effecting this transfer to a zone of

higher pressure and, as above stated, the screw pumps of gradually diminished pitch are highly inefficient and objectionable. A feature of my invention is the provision of a new improved type of pump for handling this hot powdered catalyst.

My pump comprises a chamber 23 which has at its top an inlet valve 24 communicating with collector 20 and an outlet valve 25 communicating with surge drum 26. Valves 24 and 25 are at the top of chamber 23 and the cross-sectional area of these valves takes up as nearly as economically possible the upper area of chamber 23. Chamber 23 is heavily insulated and may be provided with a heating element 27 for maintaining the desired temperature therein. Extending through packing gland 28, which may be made of a graphite-asbestos composition or other suitable material, is a reciprocating piston 29 driven by connecting rod 30 from any suitable source of power (not shown). Between the piston and the walls of chamber 23 there is a seal 31 of molten metal which may be lead but which is preferably an alloy of lead with tin, bismuth, antimony, zinc or other metal known to the art for such use. Mercury might be used as the molten metal but it is undesirable because it has a relatively high vapor pressure at the temperatures in the pump. The liquid seal should be one that does not wet the catalyst or deleteriously affect it.

In Figure 1 the piston is shown in its lowermost position having been moved downwardly to draw in a charge of aerated catalyst through open valve 24. As the piston is moved upwardly valve 24 is closed and the fluid-like aerated catalyst mixture is compressed until the pressure is sufficient to open valve 25. Continued upward movement of piston 29 expels the compressed aerated catalyst mixture through valve 25 to surge drum 26. When the piston again moves downwardly, valve 25 closes and the cycle is repeated.

It should be noted that the distance from the packing gland to the top of the piston in its lowermost position is slightly greater than the effective length of the piston stroke. This is of importance because it prevents any catalyst particles which might adhere to the piston from reaching the point at which sliding friction occurs. The molten metal seal 31 is of so much greater density than the catalyst that it prevents any catalyst material from reaching the packing gland.

While a single catalyst pump is shown in Figure 1, it should be noted that duplicate or triplicate pumps would be used in actual operation in order to maintain smooth continuous operation. The speed at which the piston moves upwardly in each pump is regulated to give a substantially constant rate of catalyst charge to surge drum 26. The design of driving means to accomplish this end is a matter of engineering skill and will, therefore, not be described in further detail.

From surge drum 26 the aerated catalyst mixture is introduced by line 32 to regenerator 33 wherein carbonaceous material is burned from the catalyst by air introduced through line 34. The regeneration is preferably at a temperature of about 1000 to 1050° F., the regenerating gas contact time is preferably about 10 to 15 seconds and the catalyst holding time in the regenerator is preferably about 1 to 10 or 15 minutes. The pressure in the regenerator may vary throughout

a considerable range but is preferably about 10 to 25 pounds per square inch, and commonly about 20 pounds above the operating pressure existing in separator 17.

The regeneration gas-catalyst mixture is then passed through line 35 to cyclone separator 36 from which regeneration gases are vented through line 37. Here again it should be understood that a number of cyclone separators may be used in series or parallel and that other suitable means may be employed for recovering the last traces of catalyst from the regeneration gases.

Regenerated catalyst passes through star feeder 38 to accumulator chamber 39 which is provided with a stripping section and an aerating section in the same way that was described in connection with chamber 20. The aerating gas in this case is preferably a flue gas introduced through line 40 and withdrawn through line 41.

Regenerated catalyst is returned from accumulator tank 39 to catalyst feed chamber 14 by means of catalyst pump 42 which functions in exactly the same manner as the catalyst pump between chamber 20 and surge drum 26.

Where there is a tendency for catalyst particles to adhere to the piston surface or where the pump structure as hereinabove described is for any other reason undesirable, I may employ a catalyst pump of the type illustrated in Figure 2. Here the pump chamber 43 is provided with a lateral packing gland 44 through which piston 45 extends. Chamber 43 contains sufficient molten metal 46 so that when the piston reaches the end of its stroke in the chamber the molten metal will substantially fill the chamber. As the piston is moved to the right the liquid molten metal level falls and thus draws into chamber 43 a charge of aerated powdered catalyst. On the return stroke of the piston the liquid level rises which closes valve 47 and compresses the aerated mixture until sufficient pressure is reached to open valve 48 after which continued rising of the liquid level in chamber 43 displaces the aerated catalyst to the zone of higher pressure.

The reciprocation of piston 45 should be relatively slow in order to prevent turbulence in the molten metal. A complete stroke of the piston may require from 5 to 60 seconds depending somewhat upon size and design of the pump. In order to avoid turbulence I may employ vertical baffles 49 or a honeycomb baffle structure to insure uniform vertical surges of the molten metal and to avoid turbulence therein. It is, of course, important to prevent any of the molten metal from being carried to the high pressure zone with expelled catalyst material but this will not present a serious problem in view of the very great density of the metal upon which the catalyst floats. Any inert layer of catalyst which may form on the surface of the molten metal is, of course, immaterial but the gas in which the catalyst is aerated should not include oxygen since it is desirable to avoid oxidation of the molten metal. The aerating gas introduced through line 21 is therefore preferably a light hydrocarbon gas and the aerating gas introduced through line 40 is preferably a flue gas.

It will be understood, of course, that the pump shown in Figure 2 will be heavily insulated and that it may also be provided with suitable heating means. The heating means are not so essential in this modification, however, because the hot catalyst which is being pumped tends to keep the molten metal from solidifying. When the system is shut down for any reason this molten metal

may be withdrawn through line 50 and a fresh charge of molten metal may be introduced through this same line when the system is again started up.

While I have disclosed preferred embodiments of my invention it will be understood that the invention is not limited to the details hereinabove set forth and that many modifications and equivalent structures will be apparent to those skilled in the art from the above disclosure. The invention is primarily applicable to the handling of powdered catalysts in hydrocarbon conversion systems but broadly it relates to the handling of abrasive powders and particularly to the transferring of abrasive powders from a low pressure zone to a high pressure zone.

I claim:

1. A system for handling a powdered abrasive solid material which comprises a collecting chamber means for introducing a powdered abrasive solid material into said collecting chamber, means for aerating the solid material in said chamber whereby the powdered solid behaves as a fluid, a pump chamber, a valve connection from said collecting chamber to said pump chamber, a discharge chamber, a valve connection between said pump chamber and said discharge chamber, a reciprocating piston in said pump chamber for drawing aerated powdered abrasive solid material from the collecting chamber into the pump chamber and for discharging said material from the pump chamber to the discharge chamber and a molten metal seal in said pump chamber for preventing solid particles from abrasive contact with said piston.

2. The system of claim 1 wherein the discharge chamber is an enlarged vessel designed to function as a surge chamber for equalizing pressure.

3. The method of transferring a powdered abrasive solid material from a low pressure zone to a high pressure zone which comprises aerating said material so that it may be handled as a fluid, withdrawing a volume of said aerated powdered solid into a compression zone, increasing the pressure on the aerated powder in said compression zone while preventing contact between powdered solid and metal surfaces which may be exposed to sliding friction, and discharging the compressed aerated powder into a high pressure zone.

4. The method of claim 3 wherein contact between abrasive powder and metal surfaces subject to sliding friction is prevented by a molten metal seal.

5. The method of claim 3 wherein the compression and transfer of the aerated powdered abrasive solid is effected by reciprocating surfaces of molten metal.

6. In a hydrocarbon conversion system employing powdered catalyst which must be transferred from a low pressure zone to a high pressure zone the method of effecting such transfer which comprises aerating said catalyst so that it behaves as a fluid, compressing said fluid while maintaining catalyst particles out of contact with metal surfaces which are subject to sliding friction and discharging said compressed aerated mixture to the high pressure zone while preventing catalyst particles from contacting said surfaces subject to sliding friction.

7. The method of claim 6 wherein contact between catalyst particles and metal surfaces subjected to sliding friction is prevented by molten metal.

8. A hydrocarbon conversion process which

comprises heating a hydrocarbon oil to reaction temperature at reaction pressure, introducing powdered catalyst into the hot oil stream, contacting the hot oil and catalyst to effect conversion of the hydrocarbon, separating powdered catalyst from the conversion products, aerating the separated catalyst so that it will behave as a fluid, compressing said aerated catalyst without permitting said catalyst to come in contact with metal surfaces subject to sliding friction, introducing said compressed aerated powdered catalyst into a regeneration zone, burning carbonaceous material from the catalyst with oxygen in said regeneration zone, separating catalyst from regenerated gases, aerating regenerated catalyst so that it behaves as a fluid, compressing said fluid without permitting the catalyst to come in contact with metal surfaces subject to sliding friction and returning said compressed aerated catalyst for further mixture with hydrocarbon oils.

9. The method of transferring aerated powdered abrasive solids having the characteristics of a fluid from a low pressure zone to a zone of higher pressure which comprises admitting said aerated solids into an enclosed space intermediate between said low pressure and high pressure zones, closing the passage connecting said low pressure zone with said enclosed space, forcing upwardly into said enclosed space a plunger substantially occupying the volume of said space and sealed relative to the walls thereof by packing means to prevent the escape of said powdered solids, thereby forcing said powdered solids into said zone of higher pressure, and separating said powdered solids and said packing means by a layer of fluid metal, the depth of which is at least equal to the length of stroke of said plunger.
